UNITED STATES PATENT OFFICE.

FREDERICK R. KALDENBERG, OF NEW YORK, N. Y.

DESIGN FOR A HANDLE FOR CUTLERY.

SPECIFICATION forming part of Design No. 18,815, dated December 18, 1888.

Application filed November 8, 1888. Serial No. 290,334. Term of patent 7 years.

To all whom it may concern:

Be it known that I, FREDERICK R. KALDENBERG, a citizen of the United States, residing at New York, in the county and State of New York, have invented and produced a new and original Design for a Handle for Cutlery, of which the following is a full, clear, and exact specification, reference being had to the accompanying drawing, which is a side elevation of a handle for cutlery, showing my new design.

The leading feature of my design consists in raised cordate figures springing from a central shield-shaped figure with volutes and leaf-like ornamentations, the whole surrounded by a scalloped shell-shaped figure.

a is the handle, which is of the usual shape, but has an irregular outline extending entirely around the same by reason of its peculiar ornamentation.

On the lower end of the handle, above a band, *b*, are two curved figures, *c c*, set to turn in opposite directions and form volutes *d d* on each edge of the handle.

*Centrally placed on the handle is the shield-shaped figure *e*, and on each side of the same, outside of its peripheral line, are three small*

volutess, *fff*. Above and below the shield-shaped figure *e*, and springing therefrom, are the cordate oblong figures *g g'* in raised outlines, which terminate in volutes *h h h*, falling within the contour-line of each figure, and from which depend the raised leaf-like ornamentations *i i*. Surmounting the upper cordate figure, *g*, is the scalloped shell-shaped figure *j*.

Near the lower end of the handle, below the cordate figure *g'*, is a diamond figure, *l*, with embossment *m*.

The outline of the two edges of the handle follows the curves of the several figures hereinbefore described.

What I claim as new, and desire to secure by Letters Patent, is—

The design for a handle for cutlery herein shown and described, comprising the cordate figures *g g'*, shield-shaped figure *e*, scalloped shell figure *j*, leaf-like ornamentations *i i*, volutes *fff*, and curved figures *c c*, as set forth.

FREDERICK R. KALDENBERG.
